DESIGN FOR A SLIPPER

Abraham Wasserman, Brooklyn, N. Y.

Application August 1, 1939, Serial No. 86,401

Term of patent 3½ years

To all whom it may concern:

Be it known that I, Abraham Wasserman, a citizen of the United States of America, residing in New York city, in the Borough of Brooklyn, county of Kings and State of New York, have invented a new, original, and ornamental Design for a Slipper, of which the following is a specification, reference being had to the accompanying drawing, forming part thereof, wherein:

Figure 1 is a top plan view of a slipper showing my new design.

Figure 2 is a side elevational view of the slipper shown in Figure 1.

The characteristic feature of my design resides in the combination on the slipper disclosed, of the toe-piece, which has a tongue sewed at the lower portion to the overlapping side pieces and continuing unattached up beyond the top of the slipper, the loose overlapping tops of the side pieces being tied over the tongue by a ribbon, as shown.

I claim:

The ornamental design for a slipper, substantially as shown and described.

ABRAHAM WASSERMAN.
